UNITED STATES PATENT OFFICE.

CHARLES C. MEUTSCH, OF CHICAGO, ILLINOIS.

COMBINED CLOTHES CLEANING, EXTRACTING, AND DRYING MACHINE.

1,158,527.

Specification of Letters Patent.

Patented Nov. 2, 1915.

Application filed June 26, 1911. Serial No. 635,361.

To all whom it may concern:

Be it known that I, CHARLES C. MEUTSCH, a citizen of the United States, and a resident of Chicago, in the county of Cook and State of Illinois, have invented certain new and useful Improvements in an Improved Combined Clothes Cleaning, Extracting, and Drying Machine, of which the following is a full, clear, and exact specification.

This invention relates to an improved combined clothes cleaning, extracting and drying machine, the performing of the functions of which has heretofore required three separate and distinct machines from which dry-cleaned clothing must be bodily transferred in open atmosphere from the cleaning machine to the extracting machine, and thence to the drier, wherein the cleansing of the clothes, as commonly practised, is accomplished by the use of gasoline or other highly volatile liquids or compounds thereof, or, in other words, by what is generally known as the "dry cleansing" process.

The prime object of my invention is to make it possible and practical to clean, extract the cleaning liquid therefrom and dry clothes in one and the same machine, and without removing them therefrom, and this in the shortest possible time, and without exposing the attendants and occupants of the room in which a cleansing machine is installed to the nauseating and intoxicating effects of the cleansing liquid, and at the same time protecting them from fire frequently occurring in the use of volatile liquids, and particularly gasoline, most generally employed, and heretofore of quite frequent occurrence.

A further object of my invention is to successfully prevent the cleansing liquid from being thrown against the joints of the casting door and by centrifugal force discharged therethrough during the cleansing operation.

A still further object of my invention is to provide means for discharging beyond the periphery of the casing and out of future contact with the clothes refuse, such as dirt, buttons, etc., due to and following the cleansing of the clothes.

With these ends in view, my invention finds embodiment in certain features of novelty in the construction, combination and arrangement of parts by which the said objects and certain other objects are herein-
55 after attained, all as fully described with

reference to the accompanying drawings, and more particularly pointed out in the claims.

In said drawings:—Figure 1 illustrates a side elevation of a combined cleansing, extracting and drying machine. Fig. 2 is a top plan view thereof with the upper portion of the casing removed and exposing the clothes containing barrel. Fig. 3 is a transverse section on the line 3—3 of Fig. 1 looking in the direction of the arrows. Fig. 4 is an enlarged detail longitudinal section on the line 4—4 of Fig. 3 looking in the direction indicated by the arrows. Fig. 5 is a similar view on the line 5—5 of Fig. 4 looking in the direction indicated by the arrows; and, Fig. 6 is a detail of the friction brake for the belt driving mechanism.

Similar characters of reference indicate the same parts in the several figures of the drawings.

Mounted at each end, upon suitable supports or standards 6, is a casing 7, preferably provided internally with a lining of zinc 8, and with a sliding manhole cover 9, confined at its ends in guides formed by the periphery of the casing and recessed bars 10, 10, as shown in Fig. 1, the lowering of which cover 9 serves to expose an opening extending the full length of the casing and providing access thereto and to the clothes therein and for the introduction of the cleansing liquid.

Extending longitudinally of the bottom of the casing is a trough 11 provided with a lining of zinc 12, preferably continuous with that of the casing, the said trough being closed at its opposite ends by means of a plate 13 seated upon a shoulder 14 of the trough, and secured upon its seat by a screw bolt 15, the bearing of which is in a bracket 16, providing means whereby accumulated refuse may be removed from the machine, the casing being preferably cylindrical in form and the trough of any form in cross section that will best subserve its purposes.

Suspended internally of the casing is a barrel 16', the walls of which are provided with a series of perforations or slits 17, which barrel is closed at its opposite ends by heads 18, to which are secured bearing plates 19, from which respectively project, through the opposite ends of the casing, short shafts 20 and 21, suitable and ordinary stuffing boxes 22 and 23 being secured

110

to the casing for preventing the cleansing liquid from discharging along these shafts.

The barrel 16' is provided with a longitudinal opening for access to clothing placed therein, closed by a door 24, provided at one edge with hinges 25 and with any suitable means, as for example thumb bolts 26, for locking in a closed position the door 24.

On the shaft 20 is a reversed gear structure, such as is commonly employed for clothes cleansing machines, and essentially comprising a loose gear 27 meshing with a pinion 28 on a short power shaft 29 on which are two loose pulleys 30 and 31, and between which is a fast pulley 32, there being also on the shaft 20 a clutch 33 actuated by a hand lever 34 for engaging and disengaging it with the gear 27, which lever 34 also actuates two driving belts (not shown) for alternately shifting the belts from the fixed pulleys 32 to the one or the other of the pulleys 30 and 31, depending upon the direction in which the barrel 16' is to be revolved.

As the details of construction of the described reverse gear actuating structure forms no part of my invention, nor does any other device which will alternately, either by hand manipulation or automatically, reverse the direction of revolution of the barrel, it will be understood that my invention is not limited to the use of any special mechanism for accomplishing this purpose, and this especially when it is old to reversely rotate the barrel of a closed cleansing machine. It is however the purpose and intention, in the practice of my invention, to use a driving mechanism therefor at one end which will automatically reverse the direction of movement of the barrel about once in every five revolutions.

So far except as to the trough 11, which is believed to be a novel feature, I have described a casing and barrel, and means for alternately reversing the direction of rotation of the barrel heretofore commonly employed for alone cleansing clothing, and for which purpose it is necessary that the barrel be reversed in its movement to keep the clothing in a loose condition for the passage therethrough of the cleansing liquid and discharge of the dirt and refuse matter therefrom, and following the completion of which the casing and the barrel are opened up, and clothing saturated and dripping with gasolene is thereupon necessarily removed by hand to another machine, commonly known and designated as the extracting machine, and wherein the gasolene or other cleansing liquid is discharged from the clothing until but little moisture remains in the clothing, when it must be removed from the extracting machine to a drying room, removing all moisture therefrom, and also the odor of the cleansing

My invention, however, contemplates and includes the extracting of the cleansing liquid and the drying and removal of the odors of the cleansing liquid without removing the clothing from the machine in which they are cleaned, and to the end that the cleansing liquid may be extracted from the clothing after being cleaned, the man-hole of the trough is opened or partially opened by unscrewing the bolt 15, the inner end of which is pivoted in the cover 13, or else discharged through a passage 15^a in the bolt 15, which passage may be closed by either a stopper or valve (not shown) and after drawing off the cleansing liquid as far as may be, following which the man-hole is closed, the gear 27 is disengaged from its clutch, and thereupon becomes an idler on the shaft 20, and thereafter the barrel is revolved at a very high rate of speed until the clothes are extracted of the liquid, as before described, by means now to be referred to.

Secured on the shaft 21 is a driving pulley 35, driven by a belt 36 on a driving pulley 37 on a shaft 38, on which is fixed a small pulley 39, and a loose pulley 39^a, the fixed pulley being actuated by a belt 40, connected with an overhead power shaft (not shown), the said several pulleys being so proportioned that the shaft 21 and the barrel may be driven at such a high rate of speed as to discharge from the clothing contained therein the cleansing liquid to a degree leaving substantially no moisture, and, in any event, only so much as may be together with its odors removed by heat.

To retard or stop the revolving of the barrel by this belt mechanism, there is mounted upon a standard 41, supported from the floor 42, a friction brake consisting of two jaws, one of which jaws 43 is fixed to the standard, and the other jaw 44 connected to the fixed jaw by a hinge 45 and normally held open by means of a coiled spring 46 seated in the opposing free edges of these jaws, which may be forced to a closed position frictionally gripping the shaft 21 by means of a foot lever 47 pivoted to the standard 41 at 48, and connecting and actuating the movable jaw 44, through the medium of a bar 49 secured at its lower end to the foot lever at 50, and at its upper end to a lug 51 projected from the movable jaw.

The casing 7 is held firm upon its standards 6, and at the same time substantially trussed, by means of bands 52, 52 at the opposite ends thereof, which extend around both the casing and the trough 11, blocks 53 being inserted against the underside of the casing, and the trough serving as a filling between the casing and the band, the ends of which terminate at the upper sides of the casing where they are provided with angular bands 54 serving as a seat for a screw bolt 55 passing therethrough for the purpose of 130

tightening these bands when from shrinkage of the casing it becomes desirable to tighten its joints and its support upon the standards, and also for loosening the band when 5 the same may be necessary.

To prevent the discharge from the casing of the cleansing liquid, when for any reason the casing is opened up, while the barrel is revolved, I suspend from the casing, by one 10 edge, a strip of felt 56, extending the entire length of the barrel and of such a width that when the barrel is revolved, as is customary, in the direction of the arrow, none of the liquid can pass beyond the felt, and to 15 which end the free edge of the felt drags upon the periphery of the barrel.

It is well known in practice that the escape of the vapors from dry cleaning machines into the room where the machine is located, and in the presence of the attendants is not only perilous to the building and the attendants from their liability to explode, but seriously affects the health and comfort of the attendants in that these odors 20 are not only disagreeable but intoxicate the attendants, and, therefore, as a means providing against these objectionable results I have connected the inside of the casing with the atmosphere outside of the room, and 25 preferably the building, by means of a pipe 57 in which is an ordinary suction fan 58 (see Fig. 1), mounted upon a shaft 59 driven by any suitable and ordinary means (not shown).

The employment of friction bearings for the shafts of the clothes cleaning machine is objectionable because of the generation of heat liable to cause an explosion of the volatile cleansing liquids commonly and 30 generally employed, which liability is increased and aggravated by the impossibility of their lubrication for the reason that gasoline, for example, gets into the bearings and cuts out the lubricant, and for obviating 35 which the bearings 60 and 61 of the shafts 20 and 21 (see Fig. 2) are provided with balls (not shown) such as are commonly employed for ball bearing surfaces, which ball bearings also serve as a means for revolving the barrel at a higher rate of speed 40 for extracting with the requirement of less power than if oil bearings were used.

For the drying of the clothing after moisture is substantially extracted therefrom, I 45 employ a convolute steampipe 62 connected with any suitable source (not shown) capable of providing a circulation of steam there-through, the steam from which, however, is shut off during both the cleansing, and for a 50 part, if not during the entire extracting operation.

In operation the casing is filled to the desired or required level with the cleansing liquid, the clothes inserted either before or 55 after the filling, the covers of the barrel and

casing closed, and the barrel revolved alternately in opposite directions by the reverse gear until the clothing is cleansed and the refuse matter substantially, if not entirely, deposited in the trough 11, whereupon the 70 cleansing liquid is drawn off together with the dirt and refuse matter, buttons, etc., through the door of the trough into some suitable receptacle (not shown), when, after settling the dirt, etc., it may be again used 75 for the same purpose.

When the cleansing liquid has been drained from the clothing as much as desired, and been discharged from the trough as far as may be, the discharge opening of 80 the trough is then closed, the gear wheel disengaged from its clutch and the belt driving mechanism set in operation to revolve the barrel at such a high rate of speed in the same direction that the cleansing liquid before remaining in the clothing will be discharged therefrom by centrifugal force through the openings in the barrel into the trough of the casing, following which this driving mechanism is thrown out of action 85 by shifting the belt 40 on to the loose pulley 39a. The cleansing liquid thus deposited in the trough is discharged therefrom in the manner before described, and following the closing of the discharge opening steam heat 90 is then supplied through the pipe 62 for such a time and at such a degree as will not only drive off all moisture contained in the clothing but the vapors through the pipe 57 into the open air, this discharge being facilitated through the medium of the suction fan 95 100 105 110 115 120 125 130 58, which should be kept in operation throughout the drying process, and may, though not necessarily, be during the cleansing and extracting process.

While I describe with great detail the construction of a combined cleansing, extracting and drying machine for clothing, and means by which the odors are prevented escaping therefrom in the presence of the attendants, and discharged outside of the building, it should be understood that my invention is not limited to these details, but finds embodiment in any machine so constructed that clothing may be dry cleaned, the cleansing liquid extracted therefrom and dried by the direct application of heat without their removal from the receptacle in which they are cleaned, until they are dried, the odors substantially removed therefrom, and ready to be pressed for use, and especially when the attendants are isolated from contact with such odors, while at the same time is avoided the necessity, previous to my invention, of removing the clothing, dipping with volatile cleansing liquid, from a cleansing machine to an extracting machine, necessarily and commonly used for discharging from the clothing their saturation with such a liquid.

Having described my invention, what I claim and desire to secure by Letters Patent is:—

1. In a combined clothes cleaning, extracting and drying machine the combination of a perforated barrel, an inclosing casing therefor, a trough depending below the same, retaining band trusses continuously surrounding said casing and trough, and
- 10 means for adjusting the tension of said bands, substantially as described.
2. In a combined clothes cleaning, extracting and drying machine, comprising in com-

bination a perforated rotatable barrel, a surrounding casing therefor and a felt strip 15 secured to the casing and bridging the space between the casing and the barrel, substantially as and for the purpose described.

In witness whereof, I have hereunto set my hand and affixed my seal, this 20th day 20 of June, A. D. 1911.

CHARLES C. MEUTSCH. [L. S.]
